UNITED STATES PATENT OFFICE

ALFRED R. OBERWEGNER, OF TOLEDO, OHIO

LAUNDRY STICK

Application filed October 20, 1927. Serial No. 227,381.

My invention has for its object to provide a laundry stick for handling clothes or manipulating wet clothes, while being laundered. The invention particularly has for its object to provide an instrument that will enable the clothes to be easily picked from the container and inserted, if desired, into a wringer.

The invention may be contained in instruments that vary in their details and, to illustrate a practical application of the invention, I have selected a laundry stick containing the invention, as an example of the improvements that embody my invention and shall describe it hereinafter. The laundry stick referred to is shown in the accompanying drawing.

Fig. 1 is a perspective view of a laundry stick embodying my invention. Fig. 2 is a side view of the end of the stick, the dimensions of the parts illustrated in Fig. 2 being shown larger than the dimensions of the corresponding parts shown in Fig. 1. Fig. 3 is a view of a section of the lower end of the laundry stick shown in Figs. 1 and 2. Fig. 4 is a perspective view of the tip of the stick which is so shaped that the wet clothing will be readily drawn from the stick by the rollers of the wringer. Fig. 5 illustrates the position of the stick with reference to a pair of rollers of the ordinary household clothes wringer.

The laundry stick shown in the drawings is provided with a handle part or rod 1, which has located at its lower end, a disc 2 that is particularly adapted to engage the wet clothing. The disc 2 is formed preferably of rubber impregnated heavy canvas so as to form a thick disc having soft rubber embodied therein and which is covered with soft rubber. The periphery of the disc protrudes laterally from the end of the stick and, by reason of the form of the disc, its edge will readily engage the wet clothing which may be lifted by raising the end of the stick. By forming the disc 2 of rubber or rubber cloth which is sufficiently rigid to maintain its form, the wet clothing will cling to the disc with greater tenacity so that, although the clothing may be caught merely by one of its corners, that is, so that only one of its cor-

ners lies over the edge of the rubber disc, yet, the clothing may be raised from the water in which it may be located during the laundering operations. The rubber impregnated fabric causes a more perfect adherence to wet clothing than where the disc is made of metal or fibre or similar materials.

The end of the stick is also provided with a rounded point or teat which is so shaped that the rotating rollers of the ordinary household wringer will readily seize the clothing that lies over the teat without drawing the teat into the wringer. Preferably the shape of the teat is substantially that shown in Fig. 4. Its shape may be described as one having a surface formed by the rotation of an ogee line about a straight line, as an axis, which will cause the delivery of the clothes to a wringer without being caught by the wringer. When the wet clothing is engaged on the edge of the disc, the stick may be raised so that the wet clothing will lie over the teat 3 and then that portion of the clothing that lies over the teat may be placed against the rotating rollers of the wringer such as the rollers 4. The rollers 4 will seize the clothing from the teat and immediately draw the clothing between the rollers. The shape of the teat is such that the clothing will slip over the surface of the teat and the teat will not enter between the rollers.

In the preferred form of the construction, the lower end of the handle 1 is provided with a collar 5 that has a flange 6 and the teat 3 is secured to the flange 6. In the particular form shown, the teat 3 has a flaring edge portion 7 and the flanges 6 and 7 are secured together by a suitable means and so as to clamp the disc 2 between the collar 5 and the teat 3 and to leave exposed the peripheral edge portion of the disc 2, substantially as shown in the Figs. 1, 2, and 3.

Thus, by my invention, clothing may be readily gathered from a tub and lifted therefrom for any purpose desired. Also the clothing may be readily positioned so as to cover the teat and may thus be readily placed in a wringer while the rollers are rotating and without handling the wet clothing with the hands of the operator. Also the rubber

flexible disc operates to protect the surfaces of the tubs or container or the interior of washing machines when it is moved in the soapy water to find any clothing as is commonly done when nearly all of the clothing has been removed.

I claim:

1. In a laundry stick, a handle part, a disc of resilient material secured centrally to the end of the handle part and extending crosswise the handle part and protruding in all directions beyond the handle part for engaging wet clothing, a substantially conically shaped teat located on the side of the disc opposite to that on which the handle is located.
2. In a laundry stick, a handle part, a disc secured to the end of the handle part and extending crosswise of the handle for engaging wet clothing, a teat located on the side of the disc opposite to that on which the handle is located, the surface of the teat having the shape of a surface formed by the revolution of an ogee line about the axis of the teat.
3. In a laundry stick for gathering clothes from liquid contained in a laundry container, a handle part having a length sufficient to reach the bottom of the container from a point above the level of the liquid contained therein, a rubber disc located on the handle part and extending crosswise the handle part and protruding in all directions beyond the handle part at the point of its connection sufficient for engaging wet clothing and holding the clothing as the clothing is lifted with the stick from the liquid.

In witness whereof, I have hereunto signed my name to this specification.

ALFRED R. OBERWEGNER.
